machine may receive the articles discharged into the receptacle 38.

A chute 40 is located in the bottom of the housing and has flanges 41 which are secured to a pair of plates 40^a and 40^b which form part of the dispensing mechanism and furthermore these plates are independent of the walls of the housing. The lower end of the chute merges into the bottom 42 of the receptacle 38. A cover plate 43 is secured at 44 to the inner face of the front wall 25 and extends downwardly and rearwardly over the receptacle 38 in such a manner that it will be impossible for someone to insert a tool through the door 35 in an attempt to operate in an unauthorized manner the dispensing mechanism. The inner elevated end of the chute 40 terminates adjacent a rear wall 45.

This machine is particularly adapted for dispensing cigarettes successively, but it will be appreciated that this machine may be employed for dispensing any other type of article by merely changing the sizes of certain elements of the dispensing mechanism without departing from the principles of the invention.

Referring more particularly to Figures 2, 4, 5 and 8 to 10, inclusive, it will be seen that the plates 40^a and 40^b are provided with flanges 59 which rest upon the bottom of the main housing. A table 51 connects the upper ends of the plates 40^a and 40^b and is formed integrally with said plates. A rear wall 52 is provided with a flange 53 which is secured in any manner to the rear edge of the table 51. This table has a depending flange 54 at its front edge as shown in Figures 2 and 3. A bar 55 is connected at its ends to the plates 40^a and 40^b adjacent the rear edge of said plates while a bar 56 is connected to the same plates adjacent the depending flange 54 of the table 51. Both of these bars are located in a plane which is below the plane of the table 51.

The table is provided at spaced points with openings 57. A pair of spaced plates 58 and 59 are provided with flanged lower ends 60 which are secured to the top of the table upon opposite sides of each opening 57. It will be noted from Figure 5 that the upper ends of these plates are flared outwardly as shown at 61 to facilitate the insertion of a box or suitable container 62 which is filled with cigarettes and has an opening at its front face at the lower end as shown at 63 whereby the cigarettes may be inspected from the exterior of the housing through the window 27. These containers or magazines are described and claimed in my co-pending application Serial No. 229,186, filed September 9, 1938. These magazines may be inserted after the window 63 has been formed and after the lower end has been opened to permit the discharge of cigarettes. Furthermore, a magazine is located between each pair of plates 58 and 59 and each magazine may contain a different brand of cigarettes.

A U-shaped member more particularly illustrated in Figures 5, 8 and 9 and generally designated by the numeral 64 is provided with a pair of depending legs 65 and 66 and a bridging member 67 which normally is disposed below an opening 57 in the table 51 for retaining the cigarettes between the plates 58 and 59. Each pair of legs of the U-shaped members is rotatably mounted upon a shaft 68 which has bearings in the bars 55 and 56. Cotter pins 69 are carried by the ends of each of the shafts for maintaining the shafts in position.

The bridging member 67 of each U-shaped member is maintained in position beneath an

opening 57 by a coil spring 70 which has one arm 71 engaging one edge of the leg 66 of the U-shaped member as shown at 72, while the other arm 73 of the spring has its end engaged over the upper edge of the bar 55 as shown at 74 in Figures 5 and 11. The coil spring 70 is mounted upon the shaft 68. A finger 75 rigid with a leg 65 has an opening 76 to receive the shaft 68.

A plate 77 is provided with bearings 78 which are received by the shaft 68 inwardly of the legs 65 and 66 of each U-shaped member and is mounted for a slight rocking movement on the shaft which is independent of the rocking movement of the U-shaped member 64. The upper edge of the plate is provided with fingers 79 which are received by notches 80 formed in the bridging member 67 of the U-shaped member 64. The outer ends of each of these fingers are provided with an angularly formed keeper 81 which is adapted to be moved through vertically disposed slots 82 formed in each of the plates 58 so that the keeper 81 may engage beneath the next of the lowermost cigarette 83 which is housed between the plates 58 and 59 for maintaining a column of cigarettes against discharge when the lowermost cigarette is being dispensed and when the bridging member 67 is moved away from its respective opening 57 as will be presently explained.

A plate 84 has its upper end 85 bent at an angle and secured to the upper end of the plate 77 so that the lower portion of the plate will extend outwardly at an angle from the plate 77. The lower rear end of the plate 84 is provided with a curved article guiding member 86. The forward lower end of the plate 77 is provided with an article guiding member 87 which is curved in an opposite direction to the member 86.

It will be seen from Figure 5 that the article guiding member 86 of one dispensing unit crosses the curved plane passing through the shorter guiding member 87 of the next adjacent unit. When a cigarette is released through any one of the openings 57 the front end will move down and fall off of the forward finger 87 while the rear end of the cigarette is still engaged by the member 86. When this happens the cigarette will be turned from its transverse position to a position which is parallel to the front face of the housing so that the cigarettes will roll into the receptacle 38 and be parallel to the door 35.

A spring member having a coil portion 90 received by the shaft 68 has an arm 91 extending upwardly therefrom and engaging over the top edge of the plate 77. The other arm 92 has a spring member which engages over the top edge of the bar 55. Thus, it will be seen that the arm 91 will tend to press the plate 77 towards the U-shaped member 64 whereby the fingers 79 will be normally seated within the notches 80 of the bridging member 67 as shown in Figure 9. The fingers 79, however, are limited in their inward movement over the openings 57 and the table 51 by the outer extreme free end 81^a engaging the upper edges 93 of the plates 58 at the upper ends of the cut out portions or openings 82 in the plates 58. When the U-shaped member 64 is rocked to the right as shown in Figure 5, the plates 77 and 84 will likewise move with the U-shaped member because of the action of the spring 90 and after the member 81 has engaged the edge 93 on the plate 58 the plates 74 and 84 will be held against further movement and the member 81 will be engaged beneath the cigarette 83. When the L-shaped member is released the

larger spring 70 will return the U-shaped member to its position beneath its respective opening 57 and the keepers 81 on the plate 71 and likewise the plates 77 and 84 will be returned to their normal inoperative position by the action of the spring 90.

A rock shaft 95 is mounted in bearings in the plates 40^a and 40^b and extends in parallel relation with the front wall 25 of the housing. A lever 96 shown more particularly in Figure 12 has a bearing 97 which is received by the shaft 95 and this lever is not only rockably mounted on the shaft but is also slidably mounted thereon. The handle 34 is rigidly connected with the lever 96 and as has been explained it extends through an elongated slot 33 in the front wall of the housing. The lever has a depending flange 98 in which is formed a socket 99 to receive a rod 100 (Figs. 3 and 4). The ends of the rod 100 are connected by legs 101 to the ends of the shaft 95 so that when the rod 100 is elevated by the raising of the lever 96 when the handle 34 is depressed the shaft 95 will be rocked. The extreme end of the flange 98 has a toe 102 which is adapted to move through one of a plurality of slots 103 (Fig. 2) formed in the bar 56 and cut through the lower end of said bar. Each slot is located adjacent one of the shafts 69 and the toe 102 moves through said slots and it will engage the finger 75 rigidly connected with a respective U-shaped member 64 for raising the member 75 and thereby oscillating the U-shaped member as shown in Figure 5.

A pointer 104 is vertically disposed from the free end of a plate 105 which has bearings 106 loosely received by the shaft 95. The inner free end 107 of the plate 105 rests upon the upper edge of the bar 56. The bearings 106 engage the opposite sides of the bearing 97 of the lever 96 so that when the lever is moved longitudinally of the shaft 95 the pointer 104 will likewise be moved but will remain stationary when the lever is rocked since the lever 96 is spaced a sufficient distance from the plate 105 which is slightly inclined from the shaft 95 to the upper end of the bar 56.

It will be seen by this arrangement that when it is desired to dispense from the machine a particular brand of cigarettes as indicated by the marker 32 in the main housing the handle 34 is moved along the slot 33 until the pointer 104 reaches the point directly at the rear of one of the labels 32 for the selected brand. The handle 34 is then depressed after a coin has been deposited in one of the coin slots 29 or 30 and the required number of cigarettes will be discharged into the receptacle in accordance with the value of the coin deposited and in accordance with the number of oscillations of said lever.

If one cent is deposited in the slot 30 the handle 34 can be depressed only once while if a nickel is deposited in the slot 29 the handle may be depressed five times and five cigarettes will be discharged into the receptacle 38.

If, on the other hand, the operator of the machine desires to obtain one or more cigarettes of one brand and the remainder of the number of cigarettes to which he is entitled of another brand, he may shift the lever to one of the brands desired and shift the pointer in alignment with one of the brands indicated by the tag 32 and operate the handle several times and then he may shift the pointer to the other brand and then operate the lever the required number of times. In this way the operator may obtain five

cigarettes each of a different brand, or he may obtain five cigarettes of one brand, or he can divide them accordingly as he sees fit by the shifting of the lever longitudinally of the slot 33 to the proper positions.

At each time the lever 34 is oscillated the member 102 engages the finger 75, raising said finger and oscillating the U-shaped member 67 to the right.

The usual fraud detecting mechanisms are employed in association with the coin chutes and since these fraud detecting mechanisms form no part of the present invention they will not be described, although they are illustrated as part of the complete machine.

An angularly shaped apron 110 (Fig. 3) is secured to the inner faces of the plates 40^a and 40^b and extends beneath the longitudinal travel of the lever 96.

A coin control mechanism is set in operation by depositing a nickel in the slot 29 which coin 111 finds its way into a terminal chute 112 (Figs. 6 and 7) and is adapted to release a locking mechanism which retains normally the lever 34 against operation.

A lever 113 is pivotally mounted intermediate its ends upon a pin 114 carried by the plate 40^a. At one side of the pivot point 114 of the lever is provided an adjustably mounted weight 115 while the opposite free end 116 of the lever is adapted to move within the chute 112 and is adapted to be engaged by the coin 111 when the coin reaches the lower portion of said chute. A bracket 117 is secured to the lever 113 and has its free end 118 perforated to receive the pin 114. A second bracket 119 is secured at 120 to the plate 40^a and has its free end pressing against the end of the pin 114 and in close association with the free end 118 of the bracket 117 for maintaining the lever in position on the pin.

A combination means for retaining the lever 113 in its lowermost position and also for retaining the prematurely inserted coin 121 in an elevated position is represented by the lever 122 which has ears 123 pivotally mounted on a pin 124 secured to the plate 40^a. A bracket 125 secured at 126 to the plate 40^a has its free end engaging the outer end of the pin 114 and likewise the outer ear 123 for maintaining the lever 122 in position on the pin. A weight 127 projects outwardly from the lever 122 and is received between the plate 40^a and the bracket 125.

A lip 128 extends outwardly from the extreme upper end of the lever 122 and projects into the coin slot 112 when the lever 113 is locked in its lowermost position for obstructing the travel of a prematurely inserted coin 121 and retains said coin in an elevated position away from the free end of the lever 116 until the coin 111 is discharged and after the lever 122 is rocked to an inoperative position whence the coin 121 will fall and again operate said lever.

A pin 129 is connected to the lever 113 adjacent the lower end of the lever 122 so that it will be engaged by a tooth 130 formed on the lower end of the lever 122. This lever also at its lower end and below the tooth 130 is provided with a finger 131 for a purpose which will be presently described. A shaft 95 projects beyond the outer face of the plate 40^a and a lever 133 at its upper end is rigidly secured to said shaft so that as the shaft is rocked the lever 133 will likewise be rocked in a direction indicated by the arrow in Figure 7.

An angularly bent pawl 134 is pivotally connected at 135 with the lower end of the lever 133

and at this portion the pawl is provided with a weight 136. The free end 137 of the pawl is adapted to engage teeth 138 formed on the periphery of a wheel 139 which is rotatably mounted on a pin 140 secured to the plate 40^a. The free end of the pawl is supported by a hanger 137^a which depends from the lever 113.

A spring 139^a has one end connected to a pin 140^a carried by the lever 113 adjacent the weight 115. The free end 141 of the spring presses upon the top of the pawl 134 and a pin 142 carried by the lever 113 is engaged by the spring 139^a so that the free end 141 of the spring will exert pressure on the pawl and maintain it in its lowermost position at the bottom of the hanger 137^a.

A strip of metal 143 is secured to the outer face of the lever 133 at 144. One end 145 of this strip is bent outwardly and forms a pocket with a raised portion 146 of the lever 133. The opposite end 147 of the strip is also bent outwardly and engages the pivoted end of the pawl 134. A pocket likewise is formed between the end 147 of the strip and the lever for a purpose which will be presently explained.

A locking device is shown at 150 (Figs. 6 and 7) and is pivoted at 151 on the plate 40^a. This locking device has a finger 152 received by the pocket located beneath the end 145 of the strip 143 and this finger is adapted to engage a lug 153 formed on the lever 133. A pin 154 projects from the member 150 and is engaged by the weighted end of the lever 113 so that when the end 116 of said lever is lowered the member 150 will be rocked and the finger 152 will be moved out of engagement with the lug 153. The member 150 as shown in Figure 7 is provided with a weight so that said member will tilt towards the weighted end of the lever 113 and maintain the pin 154 in engagement with said end of the lever.

The member 150 is also provided with a pin 155 adapted to be engaged by an arm 157 depending from a rod 156 which is supported in bearings in the plates 40^a and 40^b and this rod extends longitudinally of the housing where it projects beyond the outer face of the plate 40^b (Fig. 2).

A bar 160 is secured to the toothed wheel 139 with its opposite ends 161 and 162 extending beyond the teeth 138 of the wheel 139. The bar is provided with a laterally projecting pin 163 adjacent the end 161, while a pin 164 projects laterally from the bar and from the same face adjacent the end 162. A curved spring 165 is secured to the lever 113 and this spring is adapted to engage either one of the pins 163 or 164 when one of the ends 161 or 162 of the bar 160 is adapted to come into contact with the angularly formed free end 166 of a spring 167 secured at 168 to a bracket 169. A screw 170 connects a bracket 171 and likewise the bracket 169 to the plate 40^a. The free end of the bracket 171 engages the outer face of the bar 160 and likewise the pin 149 upon which the wheel 139 is rotatably mounted.

It will be noted that the wheel 139 has ten teeth and this wheel is adapted to be revolved through an arc of 180° so that five of the teeth will be acted upon by the pawl 134 when a nickel has been dropped into the proper coin slot and each of the ends 161 and 162 of the bar 160 will likewise be moved through 180°.

The operation of the coin control mechanism illustrated in Figures 6 and 7 is as follows: A nickel is deposited in the coin slot 29 and this coin will fall by gravity until it reaches the terminal chute 112, whence it will pass through the

chute and engage the free end 116 of the lever 113 as shown in Figure 6 where the parts are disclosed in an inoperative position and where the finger 152 of the locking element 150 is in engagement with the lug 153 on the lever 133. When the lever 113 is depressed the weighted end of said lever will raise the pin 154 and thereby tilt the member 150 on its pivot 151 whereby the finger 152 will be released from the lever 133. The lever 133 is now free to be oscillated.

The handle 34 may then be shifted by the operator until the pointer 104 is directly opposite the brand desired. The handle 34 may then be depressed five times whereby, as has been previously explained, the U-shaped member 64 will be rocked away from an associated opening 57 in the table 59 while the member 81 will engage beneath the next to the lowermost cigarette to retain the column in position while the lowermost cigarette is being released by the movement of the U-shaped member 64.

Each time the lever 133 is moved in the direction indicated by the arrow in Figure 7, the free end 137 of the pawl 134 will engage a tooth 138 of the wheel 139 and rotate the wheel step-by-step while the spring 139 presses upon the pawl to maintain said pawl in its lowermost position in the hanger 137^a.

It must be borne in mind at this time that since the lever 113 has been lowered to the position shown in Figure 8 by the coin 111 the lever 122 which is in engagement with the pin 129 will be tilted to the position shown in Figure 8 because the pin 129 will slip below the tooth 130 on the lever 122 and retain the lever in locked position and likewise the lever 113 so that the member 128 will be projected into the terminal chute 112 and the finger 131 will be moved to a position where it crosses the path of the moving end 162 of the revolving bar 160.

When the end 162 of the bar 160 approaches the free end of the spring 165 the pin 164 will be engaged by the free end of the spring and this spring will exert pressure not only on the pin but also on the bar. At about the time that the spring 165 engages the pin 164 the free end 161 of the bar will engage the bent end 166 of the spring 167 and will tend to depress the spring so that the spring will exert pressure on the end 164 of the bar. When this end of the bar passes over the raised portion 166 of the spring 167 its free end will slide rapidly beyond the raised portion and the combined action of the springs 165 and 167 will kick the bar rapidly from its vertical position so that the end 162 of the bar will be thrown against the finger 131 on the lever 122 and likewise kick this lever from its position as shown in Figure 7.

The release of the lever 122 from the pin 129 will likewise release the lever 113 so that the free end 116 of said lever will rise while the weighted end will be lowered and the weighted locking member 150 will move in the direction indicated by the arrow in Figure 8 with the pin 154 following the lowered weighted end of the lever 113. The finger 152 of the member 150 will be raised and it will engage the lug 153 on the lever 133 and thus lock this lever against further operation.

As soon as the coin 111 falls on the free end 116 of the lever 113 it will be discharged into a receptacle 171 (Fig. 6). If a second nickel had been placed in the coin slot 29 before the lever 133 had been operated five times this second coin 121 will be held in an elevated position by the finger 128 on the lever 122 since it has been pro-

jected into the terminal chute 112 as shown in Figure 7 and will be maintained in this position as long as the lever 113 is held in its lowermost position by the lever 122 and the pin 129.

After the coin 111 has moved the lever 113 to its operative position (Fig. 7) and the lever 133 has been operated five times the lever 113 will then be released by the oscillation of the lever 122. The oscillation of the lever 122 removes the finger 128 from the chute 112 whereby the coin 121 will fall immediately and again contact the free end 116 of the lever 113 and move said lever to its locked position since the tooth 130 on the lever 122 will again engage the pin 129 and lock the lever 113 in its lowermost position so that the rotatable member 139 can be revolved through 180° by the oscillation of the lever 113 five more times for dispensing five more articles.

If the previous operator had failed to obtain less than five cigarettes to which he was entitled when he deposited the coin 111, the second operator will not only receive the remaining number of cigarettes which the prior operator had failed to obtain, but he will also receive the five cigarettes to which he was entitled by the deposit of said coin 121. Thus, it will be seen that the machine will always dispense at some time or the other all of the cigarettes or articles for the value of the coins deposited.

A centrifugally operated member 175 is pivotally mounted at 176 on the lever 133 in the pocket between the end 141 of the strip of metal 143 and the outer face of the lever 133. A spring has its intermediate coiled portion 177 mounted on the pin 176. One arm 178 of the spring extends outwardly from the pocket and engages a pin 179 on the member 175. The other arm 180 is engaged around the portion 147 of the strip of metal 143 so that the arm 178 will tend to force the pin 179 and the member 175 upwardly towards a catch 181. This catch extends outwardly from a base member 182 which is secured to the plate 40a. The member 175 is provided with a notched finger 183 which is adapted to engage the catch 181 when the lever 133 is operated too rapidly and when the operator attempts to force more cigarettes or articles from the machine than the amount of money deposited. A rapid oscillation of the lever 133 will cause the member 175 to swing upwardly whereby the finger 183 will engage the catch 181 and prevent further movement of the lever 133.

I claim:

1. In a vending machine, a shaft, a lever shiftable longitudinally of the shaft, means operatively connecting the shaft with said lever so that the shaft will be rocked when the lever is rocked, a table provided with a plurality of discharge openings, individual means at each opening for retaining a column of articles in position and for releasing the articles successively, a finger on each individual releasing means adapted to be moved by the lever when said lever has been shifted along the shaft to align with said finger for rocking the releasing means away from an associated opening to discharge an article, means for retaining the remainder of the column in position when an article is discharged, and means for retaining the shaft against unauthorized operation.

2. In a vending machine, a shaft, a lever shiftable longitudinally of the shaft, means operatively connecting the shaft with said lever so that the shaft will be rocked when the lever is rocked, a table provided with a plurality of dis-

charge openings, individual means at each opening for retaining a column of articles in position and for releasing the articles successively, a finger on each individual releasing means adapted to be moved by the lever when said lever has been shifted along the shaft to align with said finger for rocking the releasing means away from an associated opening to discharge an article, means preventing operation of the lever until said lever has been properly positioned in alignment with the finger, means for retaining the remainder of the column in position when an article is discharged, and means preventing unauthorized operation of the shaft.

3. In a vending machine, a shaft, a lever shiftable longitudinally of the shaft, means operatively connecting the shaft with said lever so that the shaft will be rocked when the lever is rocked, a table provided with a plurality of discharge openings, individual means at each opening for retaining a column of articles in position and for releasing the articles successively, a finger on each individual releasing means adapted to be moved by the lever when said lever has been shifted along the shaft to align with said finger for rocking the releasing means away from an associated opening to discharge an article, means for retaining the shaft against unauthorized operation, guides depending from a pair of adjacently disposed article-releasing means for turning the articles to a dispensed position which is at right angles to the position of the articles on the releasing means, and means for retaining the remainder of the column in position when an article is discharged.

4. In a vending machine, a shaft, a lever shiftable longitudinally of the shaft, a U-shaped member projecting radially from the shaft and rigid therewith, the free end of the lever when rocked adapted to engage the bight portion of the U-shaped member for rocking the shaft, a table provided with a plurality of discharge openings, individual means at each opening for retaining a column of articles in position and for releasing the articles successively, a finger on each individual releasing means adapted to be moved by the lever when said lever has been shifted along the shaft to align with said finger for rocking the releasing means away from an associated opening to discharge an article, means for retaining the remainder of the column in position when an article is discharged, and means for retaining the shaft against unauthorized operation.

5. In a vending machine, a shaft, a lever shiftable longitudinally of the shaft, means operatively connecting the shaft with said lever so that the shaft will be rocked when the lever is rocked, a table provided with a plurality of discharge openings, individual means at each opening for retaining a column of articles in position and for releasing the articles successively, a finger on each individual releasing means adapted to be moved by the lever when said lever has been shifted along the shaft to align with said finger for rocking the releasing means away from an associated opening to discharge an article, a horizontal plate having the lower edge above the free end of the lever and adapted to be engaged by said free end to prevent operation of the lever, the lower edge of the plate having a plurality of slots, each slot being adjacent a discharge opening in the table to receive the free end of the lever and permit rocking of said lever, means for retaining the remainder of the column

in position when an article is discharged, and means preventing unauthorized operation of the shaft.

6. In a vending machine, a table having at least a pair of openings through which articles are discharged, a rockable closure for supporting a plurality of articles to be dispensed above each opening, a spring retaining each closure in an operative position, means for pivotally mounting each closure, means for rocking the closure away from an opening, a pivotally mounted finger adjacent each opening and adapted to engage the next lowermost article when the lowermost article is being dispensed, means for retaining the finger against the rockable closure, means for retaining the finger against movement after said finger has been moved to an operative position and before the closure has been moved away from the opening, a curved guide depending from one rockable closure and projecting towards the other closure, a curved guide depending from the second closure and extended towards the first-mentioned closure, said guides extending across the path of the dispensed article.

7. In a vending machine, a table having at least a pair of openings through which articles are discharged, a rockable closure for supporting a plurality of articles to be dispensed above each opening, a spring retaining each closure in an operative position, means for pivotally mounting each closure, means for rocking the closure away from an opening, a pivotally mounted finger adjacent each opening and adapted to engage the next lowermost article when the lowermost article is being dispensed, means for retaining the finger against the rockable closure, means for retaining the finger against movement after said finger has been moved to an operative position and before the closure has been moved away from the opening, a curved guide depending from one rockable closure and projecting towards the other closure, a curved guide depending from the second closure and extended towards the first-mentioned closure, said guides extending across the path of the dispensed article, one guide being shorter than the other guide whereby one end of the article will fall off the shorter guide prior to the discharge of the other end of said article from the other guide so that the

article will be turned at right angles to its former position.

8. In a vending machine, a table having at least a pair of openings through which articles are discharged, a rockable closure for supporting a plurality of articles to be dispensed above each opening, a spring retaining each closure in an operative position, means for pivotally mounting each closure, means for rocking the closure away from an opening, a pivotally mounted finger adjacent each opening and adapted to engage the next lowermost article when the lowermost article is being dispensed, means for retaining the finger against the rockable closure, means for retaining the finger against movement after said finger has been moved to an operative position and before the closure has moved away from the opening, a curved guide depending from one finger and projecting towards an adjacent finger, a curved guide depending from the adjacent finger and extended towards the first-mentioned finger, said guides extending across the path of the dispensed article.

9. In a vending machine, a table having at least a pair of openings through which articles are discharged, a rockable closure for supporting a plurality of articles to be dispensed above each opening, a spring retaining each closure in an operative position, means for pivotally mounting each closure, means for rocking the closure away from an opening, a pivotally mounted finger adjacent each opening and adapted to engage the next lowermost article when the lowermost article is being dispensed, means for retaining the finger against the rockable closure, means for retaining the finger against movement after said finger has been moved to an operative position and before the closure has moved away from the opening, a curved guide depending from each finger adjacent one end of the closure, the curved guide on one finger projecting towards the curved guide depending from the adjacent finger, said guides extending across the path of the dispensed article, one of the guides being longer than the other guide so that the article falling from the guides will be turned at right angles to its former position.

WILLIAM A. HARRIS.
